UNITED STATES PATENT OFFICE.

OLIVER McCARTHY, OF MERIDEN, CONNECTICUT, ASSIGNOR TO THE MERIDEN BRITANNIA COMPANY, OF SAME PLACE.

DESIGN FOR A COFFIN-TABLET.

SPECIFICATION forming part of Design No. 14,989, dated May 6, 1884.

Application filed February 23, 1884. Term of patent 14 years.

To all whom it may concern:

Be it known that I, OLIVER McCARTHY, of Meriden, in the county of New Haven and State of Connecticut, have invented a new Design for Coffin-Tablets; and I do hereby declare the following, when taken in connection with accompanying drawings and the letters of reference marked thereon, to be a full, clear, and exact description of the same, and which said drawings constitute part of this specification, and represent, in—

Figure 1, a face view; Fig. 2, an under edge view; Fig. 3, a vertical central section.

This invention relates to a design for the plate or tablet to be placed upon coffins; and it consists in the configuration of the tablet, as hereinafter described, and shown in the accompanying illustration.

The tablet is represented as if made from a material doubled upon itself, so that the outer fold lies upon the under, the doubled edge being rounded, the part which comes to the front diminishing in width from the doubled edge.

The surface of this overlying portion is represented as smooth, and upon which the name or other inscription is to be engraved. At the ends the exposed under portion is ornamented by tracery, as also the lower or border edge. This tracery or ornamentation may be varied to a considerable extent without departing from my design, the essential feature of which is the representation of the doubled tablet, the outer portion represented as lying upon the under portion, and contracting from the doubled side, so as to expose the under portion at each end.

I claim—

The herein-described design for coffin plate or tablet, consisting in a plate represented as doubled upon itself, the outer surface contracting from the doubled edge, as described, and shown in the accompanying illustration.

OLIVER McCARTHY.
